UNITED STATES PATENT OFFICE

129,600

DESIGN FOR A SOUNDING TOY

Alexander J. Szabo, Port Reading, N. J.

Application May 29, 1941, Serial No. 101,224

Term of patent 3½ years

To all whom it may concern:

Be it known that I, Alexander J. Szabo, a citizen of the United States of America, residing in the city of Port Reading, county of Union and State of New Jersey, have invented a new, original, and ornamental Design for a Sounding Toy, of which the following is a specification, reference being had to the accompanying drawing, forming part hereof, and in which:

I claim:

The ornamental design for a sounding toy, substantially as shown.

ALEXANDER J. SZABO.
